William J. Jackson
ATTORNEY.

Patented June 4, 1929.

UNITED STATES PATENT OFFICE.

EDWARD HUTCHINSON, JR., OF PHILADELPHIA, PENNSYLVANIA, ASSIGNOR, BY
MESNE ASSIGNMENTS, TO SAFTIGARD-NUDRIAIRE, INC., OF WILMINGTON, DELA-
WARE, A CORPORATION OF DELAWARE.

GUARD FOR ELEVATOR DOORS.

Application filed October 21, 1926. Serial No. 143,115.

This invention, generally stated, relates to elevators as used in office buildings, apartment houses, business houses and the like, and has more especial relation to the equipment of the guard gate with additional protective means for a purpose to be presently pointed out.

As at present practiced, most elevators are equipped with folding guard gates of the general type of toggle-joint arrangement. Persons within the elevator, particularly when the same is in crowded condition, frequently are crowded against such guard gate with the result that umbrellas, canes and the like frequently become caught in the guard gates and not infrequently persons' fingers are pinched between the joints of the gate when being closed by the elevator operator.

The leading object of the present invention is to overcome the above described disadvantageous features and provide an additional guard for the elevator gate by the provision of an auxiliary guard carried by the elevator and which may be moved simultaneously with the opening and closing of the guard gate, the auxiliary guard being preferably made of wire or wire mesh so that the elevator operator's vision is not obscured by the auxiliary guard.

A further object of the present invention is to provide automatic means carried by the elevator whereby the auxiliary guard automatically may wind or unwind with the closing and opening of the conventional elevator gate.

Other and further objects of the present invention reside in the provision of general details of construction and arrangement and combination of parts for attaining the results sought by the foregoing objects.

The invention consists of the novel constructions hereinafter described and finally claimed.

The nature, characteristic features and scope of the invention will be more fully understood from the following description taken in connection with the accompanying drawings forming part hereof, and in which:

Fig. 1, is a view in elevation, partly sectioned, of an elevator provided with a conventional guard gate and the auxiliary guard embodying the invention.

Fig. 2, is a view in cross section of the part shown in Fig. 1.

Fig. 3, is a similar view in which is disclosed two conventional elevator guard gates and auxiliary guards embodying the invention.

Fig. 4, is a view in elevation, partly sectioned, of one of the spring controlled rollers around which the auxiliary guard of the invention is wound and unwound.

Fig. 5, is a top or plan view of Fig. 4; and

Fig. 6, is a view in sectional plan illustrating details of construction of the roller and guard shown in the foregoing figures.

For the purpose of illustrating my invention I have shown in the accompanying drawings two forms thereof which are at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the drawings, and referring first to Fig. 2, the reference numeral 1 designates the structure of a building provided at each floor with a conventional gate 2 for closing an elevator opening 3, or passenger entrance or exit. The reference numeral 4 designates an elevator guard of any desired form. As is common practice, an elevator, as shown in Fig. 1, may be provided with a single guard gate 5, and as shown in Fig. 3 with a pair of guard gates 6. Practice dictates that in the opening and closing of the such guard gates 5 and 6, particularly when the elevator is in crowded condition, that umbrellas, canes and the like frequently become jammed within the toggle-joint parts of the gate, and not infrequently the passengers' fingers are pinched between the opening and closing parts of the gate.

In order to obviate this inconvenient and sometime dangerous condition, I provide an auxiliary guard 7, best seen in Fig. 1, and which preferably is comprised of wire mesh or the like, since the operator's vision is not obscured by wire mesh. The lower edge of the guard 7 preferably, as clearly shown in Fig. 1, may be

slightly above the floor 8 of the elevator and the upper edge of the guard 7 preferably is arranged considerably below the top 9 of the elevator opening. The outer edge of the 5 guard 7 is preferably bound by means of a strip 10, and the strip 10 is secured as by means of rivets or the like 11 to the outer edge of the guard gate 5. The strip 10 is provided with a hand grip 12. The opposite 10 parallel edge of the guard 7 is secured to the vertically disposed roller 13, best seen in Fig. 4. This roller 13 is provided at its bottom with a spindle 14, rotatably mounted in a bracket 15 carried by the elevator wall, 15 which spindle 14 and a fixed spindle 16 are connected by a coiled spring 17. The squared end 18 of the spindle 16 is fitted to the forked portion 20 of bracket 19, as clearly shown in Fig. 6, and is maintained in position by means of a cross pin 21. Thus the 20 part 18 is held in fixed relation when the guard 7 is moved to the left in Fig. 1 together with the guard gate 5. As the operator moves the guard gate 5 and the auxiliary 25 guard 7 to the right in Fig. 1, obviously the spring 17 in unwinding tends to reduce tension so that the elevator operator does not have to exert any other effort than he would naturally have to do in opening 30 the guard gate 5, the advantages of which are apparent. Fixed to the wall of the elevator cage 4, as by a screw 22, is a guard 23, best seen in Fig. 6. The purpose of this guard is to protect the roller 13 and its

guard 7 during functioning of the guard 35 gate 5 and its auxiliary guard 7.

What I claim is:

A device of the character stated comprising a building structure having an opening at a floor level, a sliding door for closing said opening, an elevator cage, a guard gate of lazy-tong construction for completely covering the opening from said cage, an auxiliary guard of relatively flexible nature mounted entirely and solely within said cage 40 to wind and unwind at one end and fixed to the free end of said gate at its other end to move therewith, said fixed end of said guard being bound by a strip 10 and riveted to said gate, said single curtain extending from adjacent the cage floor for only a portion of the height of said gate, whereby the bodies of the persons occupying the cage are protected from contact with the lazy-tong gate in closing of said auxiliary guard, a pair 45 of brackets of which one is forked, a spring actuated roller for accommodating said auxiliary guard in its winding and unwinding movements, said roller having a spindle at its bottom for engaging in one of said 50 brackets, said roller having a spindle at its top engaging the forked bracket, a coiled spring connecting said spindles, and a guard enclosing said roller.

In testimony whereof, I have hereunto 55 signed my name.

EDWARD HUTCHINSON, JR.
